HYDROFOIL CRAFT

David Z. Bailey, Charlestown, R. I.

Application January 9, 1952, Serial No. 265,551

7 Claims. (Cl. 114—66.5)

This invention generally relates to the control of longitudinal stability of water craft utilizing hydrofoil support for the purpose of reducing skin friction and displacement drag by raising the hull of the craft to a higher position with respect to the surface of the water in which it travels. In a more particular aspect, this invention concerns not only control of longitudinal stability but also control of lateral stability.

A hydrofoil is a submerged surface mounted beneath the underside of a water-borne craft which provides an upward force component or lift when the craft has forward velocity with respect to the water. If the velocity of the craft with respect to water is sufficiently high, the lift exerted on the hydrofoil by the water may be sufficient to raise the entire hull above the surface of the water, which is the desired form of travel for hydrofoil craft.

Hydrofoil craft are subject to certain disadvantages which are caused by the ever disturbed condition of the surface of almost every body of water. At a constant velocity of the craft with respect to the water, the lift force is a function of the angle of attack of the hydrofoil, i. e. angle between the water streamline and the chord line of the hydrofoil. Waves and similar disturbances produce changes in the angle of attack and the consequent change in lift tends to cause the craft to ride over the waves and to maintain a constant height above the surface. Such variations in angle of attack result in highly inefficient operation of the hydrofoil from a hydrodynamic standpoint since they may result in stalling as well as in wasted power in constantly raising and lowering the craft.

Moreover, the response of the craft to the surface configuration is always somewhat delayed, and therefore the upward reaction of the craft to a wave crest might raise the hydrofoil so near the surface of the following wave trough as to cause ventilation and serious loss of lift. Loss of lift can occur whenever the hydrofoil comes so close to the water surface that the flow of water over the hydrofoil tends to disturb the water surface.

My invention concerns principally a short period control system for hydrofoil boats which is designed to offset the effect of waves and similar disturbances so that the craft tends to ride along an even level and so that the supporting hydrofoil maintains a constant angle of attack with the streamline. In a more particular aspect my invention also permits a long period control system for depth regulation which operates independently of the short period system to maintain or adjust operation to a selected mean depth. The long period system advantageously is laterally divided to provide independent control for port and starboard and thus also provide lateral stability.

In order to secure these ends, I provide in addition to the main hydrofoil a secondary or control hydrofoil mounted beneath the underside of the craft and free to assume an approximately streamline path both vertically and in pitch angle. The control hydrofoil is directly con-

2

nected to the main hydrofoil so that the pitch angle of the main hydrofoil correspondingly and equally reflects changes in the pitch angle of the control hydrofoil induced by changes in the direction of flow of water past the control hydrofoil (short period system). In addition, means are provided to adjust the phase relation between the pitch angles of the control and main hydrofoils for the purpose of varying the equilibrium height of the craft above the water (long period system). Such means are connected so as not to interfere with the free movement of the control hydrofoil.

In the drawings:

Figure 1 is an isometric view of a water craft utilizing my invention. Figure 2 is a schematic diagram illustrating the mode of operation of the craft in Figure 1.

Figure 3 is an enlarged view of a control system of another craft identical to that shown in Figure 1 but also utilizing a system for controlling lateral stability coordinated with the long period stability control system.

Figures 4, 5, 6, 7, 8 and 9 describe a third craft identical to that in Figure 3, but also utilizing a system for varying the lift coefficient of the main hydrofoil.

Figure 4 is a plan view of a portion of the control system, while Figures 5 and 6 are sectional elevations of the apparatus shown in Figure 4 taken along lines 5—5 and 6—6, respectively.

Figure 7 is a horizontal section of another portion of the third craft, while Figure 8 is a vertical section of the apparatus shown in Figure 7 taken along line 8—8 in Figure 7. Figure 9 is a front view shown partially in section of the apparatus shown in Figures 7 and 8 taken at line 9—9 in Figure 8.

Referring to Figures 1 and 2 of the drawings, the reference numeral 1 represents a hydrofoil water craft embodying a simple illustration of my invention. Hydrofoil craft 1 comprises a hull 2 of conventional shape having mounted thereon, by means of hollow supporting struts 3 and horizontal beam 4, a main hydrofoil 5. Struts 3 and hydrofoil 5 are of streamline cross-section so as to reduce frictional drag through the water as much as possible. Hydrofoil 5 is pivoted to struts 3 at points 6.

The craft is provided with a rudder assembly 7 comprising a tiller 8, strut rudder 9 and stabilizer hydrofoil 10. Preferably, stabilizer hydrofoil 10 is of adjustable pitch angle, by means of sheave 11 and line 12 which is fixed at its ends to the leading and trailing surfaces of hydrofoil 10. Sheave 11 is rotatable by tiller 8 to permit manual adjustment for proper trim for any given center of gravity or propulsion thrust effect on hull pitching moment.

An approximately vertically positioned strut 13 of streamline cross-section passes downwardly through an aperture 14 in craft 1 and terminates at its lower end below the underside of the craft 1. Control hydrofoil 15 is mounted in front of strut 13 by lever arm 16 which is fixed at end 17 to control hydrofoil 15 and pivoted to strut 13 at point 18 intermediate the length of arm 16. Strut 13 is supported by a second lever arm 19 lying in the same vertical plane as, and parallel to, lever arm 16. Lever arm 19 is pivotally mounted to craft 1 at point 20 and is pivotally connected to the upper portion of strut 13 at point 21 intermediate the length of arm 19. A third lever arm 22, lying in the same vertical plane as, and parallel to, lever arms 16 and 19, is pivotally connected at its end 23 with strut 13. The pivot point 23 lies on the imaginary line determined by points 21 and 18. Lever arm 22 is pivotally connected at its other end with craft 1 at point 24A which is determined by the point of intersection of arm 22 with an imaginary line passing through point 20 parallel to the imaginary line determined by points 21 and 18. The free ends 24 and 25 of lever arms 19 and 16, respectively, are linked by connecting

rod 26 which is parallel to the imaginary line determined by points 21 and 18. Lever arm 19 is connected at point 20 by direct axle connection with sheave 27. The length of lever arm 16 from pivot point 25 to the forward tip of control hydrofoil 15 must be substantially less than the distance on lever arm 19 between pivot points 20 and 24.

The pitch of hydrofoil 5 is controlled by cable 28 which is wound over sheave 29 mounted to beam 4 and is fastened to hydrofoil 5 at point 30 on the leading surface point 31 on the trailing surface. Preferably, the sheave and line arrangement is duplicated at each end of hydrofoil 5. Cables 28 pass down through the centers of hollow struts 3. Sheaves 29 are mounted on a common axle 32 which traverses beam 4 of craft 1. Sheave 33 is mounted on axle 32 in line with sheave 27 and has a diameter twice that of sheave 27. Forward of sheave 33 and in line with it is positioned sheave 34 which is suitably mounted to the deck of craft 1 and which is rotatable by crank 35.

Cable 36 attached to pulley block 37 and pulley block 38 passes around sheave 27. A continuous cable 39 is passed from the underside of sheave 33 to the underside of pulley sheave 40 mounted in pulley block 37, from the upper side of pulley sheave 40 to the underside of sheave 34, from the upper side of sheave 34 to the underside of pulley sheave 41 mounted in pulley block 38 and from the upper side of pulley sheave 41 to the upper side of sheave 33.

Figure 2 illustrates more clearly the mechanism by which the control hydrofoil 15 operates to vary the pitch angle of main hydrofoil 5.

If, for example, there is a downward velocity of the boat or an upward velocity of the water due to some disturbance such as the crest of a wave passing control hydrofoil 15, then there is an increase in lift on control hydrofoil 15 because the effective angle of attack of the control hydrofoil is increased. The added lift will cause control hydrofoil strut 13 to rise with respect to the boat thereby causing lever arms 22 and 19 to rotate about their forward pivots 24A and 20, respectively. By means of connecting rod 26, lever arm 16 is made to rotate in a similar manner and to decrease the angle of attack until hydrofoil 15 assumes a new equilibrium position with respect to the water flowing past it. Such equilibrium position is, of course, approximately a streamline position with just sufficient angle of attack to exert enough lift to support the free weight of strut 13 and its associated lever arm mechanism. The dotted line position in Figure 2 illustrates such a new equilibrium point caused by a downward velocity of the boat or an upward velocity of the water. It will be observed that inherently the movement imparted to control hydrofoil 15 by its supporting structure, as hydrofoil 15 moves from one equilibrium position to another in following a streamline path, is about a pivot axis which extends horizontally and which is located forward of control hydrofoil 15 transversely passing through the intersection A of an imaginary line through pivots 20 and 24A with an imaginary line passing through pivots 18 and 25.

The movement of lever arm 19 in response to such changes in the equilibrium position of hydrofoil 15 causes sheave 27 to rotate, which rotation is translated into a change of position of pulley blocks 37 and 38 by means of cable 36. In ordinary operation crank 35 is secured in one position so that sheave 34 remains stationary. Hence, the movement of pulley blocks 37 and 38 causes a corresponding rotation in sheave 33 due to the movement of cable 39 induced by such change in position of pulley blocks 37 and 38. Since sheave 33 has twice the diameter of sheave 27, it is displaced through an angular change equal to the angular displacement of sheave 27. Sheave 33 causes sheaves 29 to rotate equally since they are connected by common axle 32 and thus the motion of hydrofoil 15 is communicated directly and equally to hydrofoil 5, thus causing its lift to decrease,

thereby tending to offset the effect of the downward velocity of the craft or upward velocity of the water which induced the change in position of hydrofoil 15 and to maintain hydrofoil 5 at a constant angle of attack with the streamline.

However, the short period system which I have just described is not complete. I have found it is also necessary to provide a mechanism for independently adjusting to new boat velocities or to allow for vertical accelerations. In addition, the boat might slowly sink or rise due to inability of a small change in lift on the control hydrofoil 15 to move the control system because of the friction in the system. When it is desired to change the vertical position of the craft with respect to the water, it is necessary to rotate main hydrofoil 5 while maintaining control hydrofoil 15 in the same position. This is accomplished by providing an independent mechanism for adjusting the pitch angle of main hydrofoil 5 without affecting the pitch angle of control hydrofoil 15. That is, a means is provided to adjust the phase relation between the pitch angles of control hydrofoil 15 and main hydrofoil 5.

In the craft illustrated in Figures 1 and 2 such an independent control mechanism is crank 35 and sheave 34 which are coordinated with the operation between sheaves 27 and 33 by pulleys 37 and 38. Thus, changing the position of crank 35 causes sheave 34 to rotate. Such rotation is translated to sheave 33 and thereby to main hydrofoil 5. The position of control hydrofoil 15, of course, is entirely independent of such operation and is not effected by it.

The long period system, that is, the independent control of the phase relation between the pitch angles of the control and main hydrofoils, is more usefully controlled by automatic rather than by human response. While the pilot is able to control the craft shown in Figure 1, the adjustment of crank 35 is difficult at best. Moreover, the pilot will not always react fast enough and will have difficulty in judging the degree of correction needed.

It is best, therefore, in the interests of safety to effect the change in pitch angle relation by utilizing a conventional depth sensor which measures the depth at the hydrofoil or some other convenient point based on the conversion of hydrodynamic energy into electrical energy. For example, a Pitot static tube with static pressure holes advantageously is arranged with a resistance type strain gauge (or a slide wire and piston) so that the resistance of the strain gauge is a function of the static pressure at the holes. An electrical control circuit is governed by the strain gauge and is adjusted so that operation may be set for any desired actual depth at the point of measurement. The electrical control circuit is used to energize a motor which is geared to drive sheave 34 in accordance with deviations from the desired depth.

It should be noted that the short period system not only remains unaffected by changes in the phasing of the pitch angles of main hydrofoil 5 and control hydrofoil 15, except insofar as such changes may momentarily require a readjustment of control hydrofoil 15 to a new equilibrium position, but also hydrofoil 15 is only negligibly affected by the pitching moment of hydrofoil 5 since pivot points 6 are located approximately at the ends of the theoretical line across the span of hydrofoil 5 about which all force components are exerted, thus the reaction load is carried principally by pivot points 6, and since a considerable mechanical advantage exists between hydrofoil 15 and hydrofoil 5.

The utilization of such a long period system facilitates control of lateral stability as well as longitudinal stability. That is, the main hydrofoil may be divided by a central strut into two sections each independently controlled for desired depth by a Pitot tube located at the lower end of the adjacent outside strut. Each main hydrofoil continues to be controlled in the same degree by the control hydrofoil.

Figure 3 is a close-up view of the central portion of a hydrofoil craft similar to that shown in Figure 1 but which also utilizes a system of lateral stability control. In the figure, the parts not shown are identical with those in Figure 1. Where I have used the same numbers, it is to be understood that the same part is intended. Also in the designation of the parts I have utilized the suffix "a" to designate all the parts which are specific to the port side of the craft and the suffix "b" to designate all the parts specific to the starboard side of the craft where such parts are symmetrically disposed on both port and starboard.

It will be noted that the craft illustrated in Figure 3 utilizes an identical control system as the craft shown in Figure 1. However, from pulley blocks 37' and 38' to hydrofoils 5a and 5b the system is divided into two corresponding halves, each half corresponding in operation to the operation between pulley blocks 37 and 38 and hydrofoil 5 of craft 1 in Figure 1. Craft 1' is provided with a central strut 3' which divides main hydrofoil 5 into two sections 5a and 5b. The use of the central strut permits control of each main hydrofoil 5a and 5b by passing cables 28a and 28b through the central strut rather than requiring the need of an axle 32 and additional sheaves 29 as in Figure 1.

Pulley blocks 37' and 38' each carry a pair of pulley sheaves, 40a and 40b, and 41a and 41b, respectively. Sheave 34 of Figure 1 is replaced by two independently mounted sheaves 34a and 34b which are driven by electric motors 42a and 42b through screw drive transmissions 43a and 43b, respectively. Motors 42a and 42b are controlled by the hydrostatic pressure at Pitot static tubes 44a and 44b, respectively, mounted in struts 3. Sheave 33 of the craft in Figure 1 is replaced by a pair of independently mounted double grooved sheaves 45a and 45b.

Continuous cables 39a and 39b are substituted for single cable 39 of the craft in Figure 1. Thus cable 39a traverses sheave 45a, pulley sheave 40a, sheave 34a and pulley sheave 41a in the same manner that cable 39 traverses sheave 33, pulley sheave 40, sheave 34 and pulley sheave 41, respectively, in Figure 1. Cable 39b is correspondingly mounted about sheave 45b, pulley sheave 40b, sheave 34b and pulley sheave 41b, respectively. Cables 28a and 28b attached to hydrofoils 5a and 5b, respectively, are passed through the second groove of sheaves 45a and 45b, respectively, and are housed within hollow center strut 3'.

As the craft is passing through the water, disregarding for the moment the operation of the two long period control systems, any change in position in control hydrofoil 15 is transmitted to pulley blocks 37' and 38' as in the operation of the craft in Figure 1. So long as the two long period systems are inoperative, sheaves 34a and 34b remain stationary and therefore hydrofoils 5a and 5b are caused to change their pitch angle in exactly the same amount as control hydrofoil 15 is changed by whatever disturbance moves it.

However, as soon as either side of the craft changes in depth from the desired and selected depth of operation, the change in static pressure of the Pitot static tube energizes operation of its corresponding lateral control system. For example, assume that the port side of craft 1 sinks due to a change in the loading of the craft, the increase in hydrostatic pressure measured at Pitot tube 44a causes motor 42a to turn sheave 34a so as to increase the pitch of hydrofoil 5a in the same manner that rotation of sheave 34 changes the pitch in the craft in Figure 1, and thus returns craft 1 to an even keel, motor being de-energized when the desired depth is again attained. This same action, of course, is effective on both port and starboard and operates to maintain the craft on an even keel as well to control the desired depth of operation as in Figure 1. During turning operations the

pilot can change the desired depth for each side to different values and thus obtain the necessary bank for turning.

The same type of long period control system may be coordinated to vary the mean camber of the hydrofoil. Figures 4, 5, 6, 7, 8 and 9 illustrate a modification of the device shown in Figure 3 for effecting such a change in mean camber of the main hydrofoils. Where I have used the same numbers, the same parts are intended as in Figures 3 and 1, and their operation will be identical with that of the operation in Figure 3. Also, the use of the subscripts "a" and "b" has been retained with the same meaning as in Figure 3.

Referring first to Figures 7, 8 and 9 to illustrate the change in hydrofoil structure, it will be noted that Figure 8 is a cross-section taken through hydrofoil 5a looking toward center strut 3'. Hydrofoil 5a is divided spanwise into two principal sections. Main span 46a is a wedge shaped piece extending through three-quarters of the cord line of hydrofoil 5a. The first quarter of hydrofoil 5a is a sharp pointed circular arc nose flap 47a. Leading edge (nose flap) 47a is movably fixed to main span 46a by spring steel strip 49a and stretched rubber strip 48a.

Referring now to Figures 4, 5 and 6 which illustrate the adjustment in the pulley system to accommodate a control system of the flap angle, it will be seen that the system of Figure 3 has been duplicated. However, an additional pair of symmetrically disposed systems have been added, so that each pulley block 37' and 38' now carries 4 pulley sheaves instead of 2 as in Figure 3. To motor driven sheaves 34a and 34b have been added additional sheaves 51a and 51b, respectively, of three times the diameter of sheaves 34a and 34b. Double grooved sheaves 45a and 45b have been combined with additional elements to produce compound sheaves 50a and 50b, respectively.

Sheave 50a, working from inside out, comprises double grooved sheave 45a which is axially mounted to rotate freely, groove edged plate 57a which is pivotally connected on pin 58a with sheave 45a, link 59a which is pivotally connected with plate 57a by pin 60a, and outside sheave 56a which is pivotally connected to link 59a by pivot pin 61a. Outside sheave 56a is single grooved, is axially mounted to rotate freely, and is of the same diameter as sheave 45a. The distance of pivot pin 58a from the center of sheave 45a is equal to the distance between pivot pins 60a and 61a on link 59a. The distance of pivot pin 61a from the center of sheave 56a is equal to the distance between pivot pins 58a and 60a on plate 57a. Sheave 50b is, of course, the symmetrical counterpart of sheave 50a.

In the cable and pulley connection arrangement cable 54a is continuous and passes from the bottom of sheave 56a to the bottom of pulley sheave 52a, from the top of pulley sheave 52a to the top of sheave 51a, from the bottom of sheave 51a to the bottom of pulley sheave 53a and from the top of pulley sheave 53a to the top of sheave 56a.

Figure 4 is an elevation view of the arrangement of all four cables 39a and 39b, and 54a and 54b. Figure 5 is a cross-section taken along line 5—5 in Figure 4 and shows exclusively the arrangement of cable 54a which is a duplicate of the arrangement of cable 54b. In Figure 5 sheave 56a is partially cut away to show the internal arrangement of compound sheave 50a.

Figure 6 is a section through Figure 4 along line 6—6 and shows exclusively the arrangement of cable 39b. In Figure 6 double sheave 45b is partially cut away to show the internal arrangement of parts in compound sheave 50b which in all respects is a mirror image of sheave 50a.

Control cables 28a and 28b which control main hydrofoil spans 46a and 46b are wound over the second grooves of sheaves 45a and 45b, respectively, and pass down through central strut 3'. Control cables 62a and

62b which adjust the flap angles of flaps **47a** and **47b**, respectively, pass over grooved plates **57a** and **57b**, respectively, and also are fed downwardly through central strut **3'**.

Referring now to Figures 7, 8 and 9, it will be noted that main span **46a** is bolted to a plate **55a** and pivoted on pin **63** to strut **3'**. Span **46b** is similarly pivoted. Cables **28a** and **28b** are fastened to the ends of plates **55a** and **55b**, respectively, and thus translate the motion of control hydrofoil **15** to the main span hydrofoils **46a** and **46b** as before (Figure 3). Flap angle control cables **62a** and **62b** are connected to the ends of plates **64a** and **64b**, respectively, which are bolted at their forward ends to nose flaps **47a** and **47b** and are pivoted on pins **65a** and **65b** to plates **55a** and **55b**, respectively, the point of pivot being adjusted in the illustrated case at the quarter cord distance and along the upper surface of the foil.

Referring back to Figures 4, 5 and 6, for the moment, each of grooved plates **57a** and **57b** is formed having opposite arcuate edges about pivot pins **58a** and **58b**, respectively, as centers. Each of pivot pins **58a** and **58b** is located in its respective plate **57a** or **57b** so that one such arcuate edge is constructed with three times the radius of the opposite arcuate edge. Thus the portion of each of cables **62a** and **62b** leading to the forward edge of each of plates **64a** and **64b**, respectively, will be moved through one-third the distance through which the other end of the cable moves, as each of plates **57a** and **57b** is rotated about pivot pin **58a** and **58b**, respectively. It will be apparent that each of plates **57a** and **57b** has the same angular geometry as each of plates **64a** and **65b**, and thus angular motion about pivot **58a** or **58b** is duplicated about pivot **65a** and **65b**, respectively, while angular motion about the central axes of sheaves **50a** and **50b** is duplicated about pin **63**.

In operation, when the long period control system is stationary, it will be seen that any motion in hydrofoil **15** is directly translated equally to both main spans **46a** and **46b** of hydrofoils **5a** and **5b**. By the same motion each of sheaves **56a** and **56b** will be caused to move through the same angle of rotation as double sheaves **45a** and **45b** and hence plates **57a** and **57b** will also exhibit the same degree of turn about the axial lines of sheaves **56a** and **45a**, and **56b** and **45b**, respectively. Since plates **57a** and **57b** rotate through the same angle as sheaves **45a** and **45b** and sheaves **56a** and **56b**, respectively, and since cables **62a** and **62b** are substantially parallel to cables **28a** and **28b**, the flap deflection angle of hydrofoils **5a** and **5b** remains substantially constant.

However, when the long period system of either side is caused to operate, due to the geometry of the system, the flap angle is given three times the effect and in an opposite direction as the main hydrofoil span. Assume, for example, that it is desired to increase the lift of hydrofoil **5a**, this is done by increasing its angle of attack by energizing motor **42a** which causes its associated sheaves **51a** and **34a** to rotate at a slow rate of speed. Assuming that control hydrofoil **15** remains in a stationary position, this rotation will cause cable **54a** to rotate three times as much as cable **39a** since sheave **51a** has three times the diameter of sheave **34a**. Moreover, the movement of the cables **39a** and **54a** will be in opposite directions. Since the geometry of plate **57a** is such that it is pivoted with respect to sheave **45a** at the same relative point as nose flap plate **64a** is with respect to main span plate **55a**, the opposite and threefold angular rate of movement induced in plate **64a** will cause nose flap **47a** to be deflected downwardly with a flap deflection three times as great as the increase in pitch of span **46a**.

It will be obvious to those skilled in the art that certain changes other than those I have suggested may be made in the described water craft. For example, hydrofoil **15** may be positioned aft of strut **13**. Its operation

will produce identical results. However, it should be remembered that the water disturbance created by strut **13** will, in a degree, reduce the sensitivity of hydrofoil **15**. For that matter, hydrofoil **15** can be placed with its associated support mechanism aft of the main hydrofoil. The same objections however can be made against the desirability of such practice. One convenient alternative arrangement is to place strut **13** and connecting rod **26** inside central strut **3'** with a slit in the leading edge of strut **3'** to allow lever arm **16** to move up and down holding hydrofoil **15** out ahead.

The pulley assemblies above decks may readily be replaced by equivalent mechanical linkages, for example, by cranks and a connecting rod having an adjustable connection such as a slid able pivot point. Or lever arm **19** might turn an axle which drives the rotor of a self-synchronous motor having its stator connected in parallel to the stator of another self-synchronous motor, both having their rotors connected to a common A. C. supply, which second motor would be used to drive axle **32**. Or an angularly responsive electrical mechanism, such as a self-synchronous transmitter, might be positioned at pivot point **25** utilizing a servo mechanism to produce equal changes in hydrofoil **5**, or hydrofoils **5a** and **5b**, as the case may be. In such cases, phase adjustment could be made either electrically by known methods or by a mechanical system involving a transmission and clutch. Along the same idea the pulley and cable arrangements of the craft shown in Figure 3 and of the craft shown in Figures 4-9 may be substituted by obvious mechanical and electrical equivalents.

It will be noted that I have omitted any description of a propulsion system. I contemplate the use of any of the marine propulsion systems utilized in hydrofoil type craft. In particular, air propulsion is extremely well adapted to hydrofoil craft as it provides minimum disturbance of the water passing the hydrofoils.

I claim:

1. In a water craft having a main hydrofoil pivotally supported below the level of the underside of the craft which hydrofoil is inclinable to provide an upward force component by dynamic action with the water when the craft has forward velocity with respect to the water, the improvement which comprises a control hydrofoil; an approximately vertically positioned strut passing downwardly through the craft, free to move in approximately vertical directions with respect to the craft, and terminating at its lower end beneath the underside of the craft; a first lever arm lying in approximately the fore and aft direction of said craft, fixed at one end to said control hydrofoil, and pivotally connected at a point intermediate its length with the lower end of said vertical strut; a second lever arm lying in the same vertical plane as, and parallel to, said first lever arm, pivotally connected at one end with said craft, and pivotally connected at a point intermediate its length with the upper portion of said vertical strut; a third lever arm lying in the same vertical plane as, and parallel to, said first and second lever arms, pivotally connected at one end with said vertical strut along the imaginary line determined by the pivotal connections of said first and second lever arms with said strut, and pivotally connected at its other end with said craft at the point determined by its intersection of the imaginary line passing through the pivotal connection of said second lever arm with said craft parallel to the imaginary line determined by the pivotal connections of said first and second lever arms with said strut; a connecting rod parallel to the imaginary line determined by the pivotal connections of said first and second lever arms with said strut, and pivotally connected at its ends with the free ends of said first and second lever arms; linkage connecting said control hydrofoil and said main hydrofoil, whereby changes induced in the angular position of said control hydrofoil are reflected by corresponding changes in the angular position of said main hydro-

foil; and means independent of the angular position of said control hydrofoil for varying the phase relation of the angular positions of said control and main hydrofoils.

2. In a water craft having a main hydrofoil pivotally supported below the level of the underside of the craft which hydrofoil is inclinable to provide an upward force component by dynamic action with the water when the craft has forward velocity with respect to the water and which main hydrofoil is divided into an independent port hydrofoil and an independent starboard hydrofoil; the improvement which comprises a control hydrofoil; an approximately vertically positioned strut passing downwardly through the craft, free to move in approximately vertical directions with respect to the craft, and terminating at its lower end beneath the underside of the craft; a first lever arm lying in approximately the fore and aft direction of said craft, fixed at one end to said control hydrofoil, and pivotally connected at a point intermediate its length with the lower end of said vertical strut; a second lever arm lying in the same vertical plane as, and parallel to, said first lever arm, pivotally connected at one end with said craft, and pivotally connected at a point intermediate its length with the upper portion of said vertical strut; a third lever arm lying in the same vertical plane as, and parallel to, said first and second lever arms, pivotally connected at one end with said vertical strut along the imaginary line determined by the pivotal connections of said first and second lever arms with said strut, and pivotally connected at its other end with said craft at the point determined by its intersection of the imaginary line passing through the pivotal connection of said second lever arm with said craft parallel to the imaginary line determined by the pivotal connections of said first and second lever arms with said strut; a connecting rod parallel to the imaginary line determined by the pivotal connections of said first and second lever arms with said strut, and pivotally connected at its ends with the free ends of said first and second lever arms; linkage connecting said control hydrofoil and each of said main hydrofoils, whereby changes induced in the angular position of said control hydrofoil are reflected by corresponding changes in the angular positions of each of said main hydrofoils; and a pair of means independent of the angular position of said control hydrofoil, one for varying the phase relation of the angular positions of said control and said port main hydrofoils, and the other for varying the phase relation of the angular positions of said control and said starboard main hydrofoils.

3. In a water craft having a main hydrofoil pivotally supported below the level of the underside of the craft which hydrofoil is inclinable to provide an upward force component by dynamic action with the water when the craft has forward velocity with respect to the water and which main hydrofoil is divided into an independent port hydrofoil and an independent starboard hydrofoil; the improvement which comprises a control hydrofoil; an approximately vertically positioned strut passing downwardly through the craft, free to move in approximately vertical directions with respect to the craft, and terminating at its lower end beneath the underside of the craft; a first lever arm lying in approximately the fore and aft direction of said craft, fixed at one end to said control hydrofoil, and pivotally connected at a point intermediate its length with the lower end of said vertical strut; a second lever arm lying in the same vertical plane as, and parallel to, said first lever arm, pivotally connected at one end with said craft, and pivotally connected at a point intermediate its length with the upper portion of said vertical strut; a third lever arm lying in the same vertical plane as, and parallel to, said first and second lever arms, pivotally connected at one end with said vertical strut along the imaginary line determined by the pivotal connections of said first and second lever arms with said

strut, and pivotally connected at its other end with said craft at the point determined by its intersection of the imaginary line passing through the pivotal connection of said second lever arm with said craft parallel to the imaginary line determined by the pivotal connections of said first and second lever arms with said strut; a connecting rod parallel to the imaginary line determined by the pivotal connections of said first and second lever arms with said strut, and pivotally connected at its ends with the free ends of said first and second lever arms; linkage connecting said control hydrofoil and each of said main hydrofoils, whereby changes induced in the angular position of said control hydrofoil are reflected by corresponding changes in the angular positions of each of said main hydrofoils; a first pair of means independent of the angular position of said control hydrofoil, one for varying the phase relation of the angular positions of said control and said port main hydrofoils, and the other for varying the phase relation of the angular positions of said control and said starboard main hydrofoils; and a second pair of means independent of the angular position of said control hydrofoil, coordinated with said first pair, one for varying the mean camber of said port main hydrofoil, and the other for varying the mean camber of said starboard main hydrofoil.

4. In a water craft having a main hydrofoil pivotally supported below the level of the underside of the craft which hydrofoil is inclinable to provide an upward force component by dynamic action with the water when the craft has forward velocity with respect to the water; the improvement which comprises a control hydrofoil; means supporting said control hydrofoil below the level of the underside of the craft, said control foil being movable about a horizontally extending pivot axis forward of said control foil whereby said control hydrofoil assumes an approximately streamline path through the water beneath the surface thereof when said craft has forward velocity with respect to the water; linkage connecting said control hydrofoil and said main hydrofoil, whereby changes induced in the angular position of said control hydrofoil are reflected by corresponding changes in the angular position of said main hydrofoil; and means independent of the angular position of said control hydrofoil for varying the phase relation of the angular positions of said control and main hydrofoils.

5. In a water craft having a main hydrofoil pivotally supported below the level of the underside of the craft which hydrofoil is inclinable to provide an upward force component by dynamic action with the water when the craft has forward velocity with respect to the water and which main hydrofoil is divided into an independent port hydrofoil and an independent starboard hydrofoil; the improvement which comprises a control hydrofoil; means supporting said control hydrofoil below the level of the underside of the craft, said control foil being movable about a horizontally extending pivot axis forward of said control foil whereby said control hydrofoil assumes an approximately streamline path through the water beneath the surface thereof when said craft has forward velocity with respect to the water; linkages connecting said control hydrofoil and each of said main hydrofoils, whereby changes induced in the angular position of said control hydrofoil are reflected by corresponding changes in the angular positions of each of said main hydrofoils; and a pair of means independent of the angular position of said control hydrofoil, one for varying the phase relation of the angular positions of said control and said port main hydrofoils, and the other for varying the phase relation of the angular position of said control and said starboard main hydrofoils.

6. In a water craft having a main hydrofoil pivotally supported below the level of the underside of the craft which hydrofoil is inclinable to provide an upward force component by dynamic action with the water when the craft has forward velocity with respect to the water and

which main hydrofoil is divided into an independent port hydrofoil and an independent starboard hydrofoil; the improvement which comprises a control hydrofoil; means supporting said control hydrofoil below the level of the underside of the craft, said control foil being movable about a horizontally extending pivot axis forward of said control foil whereby said control hydrofoil assumes an approximately streamline path through the water beneath the surface thereof when said craft has forward velocity with respect to the water; linkages connecting said control hydrofoil and each of said main hydrofoils, whereby changes induced in the angular position of said control hydrofoil are reflected by corresponding changes in the angular positions of each of said main hydrofoils; and a pair of means independent of the angular position of said control hydrofoil, one for varying the phase relation of the angular positions of said control and said port main hydrofoils, and the other for varying the phase relation of the angular position of said control and said starboard main hydrofoils; and a second pair of means independent of said control hydrofoil coordinated with said first pair, one for varying the mean camber of said port main hydrofoil and the other for varying the mean camber of said starboard main hydrofoil.

7. In a water craft having a main hydrofoil pivotally supported below the level of the underside of the craft; the improvement which comprises a control hydrofoil; means supporting said control hydrofoil below the level of the underside of the craft, said control foil being movable about a horizontally extending pivot axis forward of said control foil whereby said control hydrofoil assumes an approximately streamline path through the water beneath the surface thereof when said craft has forward velocity with respect to the water; and linkage connecting said control hydrofoil and said main hydrofoil, whereby changes induced in the angular position of said control hydrofoil are reflected by corresponding changes in the angular position of said main hydrofoil.
